Primary Examiner — Marianne Pandozzi(74) *Attorney, Agent, or Firm* — Millen, White, Zelano & Branigan, P.C.; William Nixon(57) **CLAIM**

The ornamental design for an atmospheric water generator floor unit, as shown and described.

DESCRIPTION

FIG. 1 is a front-left side perspective view of an atmospheric water generator floor unit showing my new design;

FIG. 2 is a rear-right side perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof; and,

FIG. 8 is a bottom plan view thereof.

The broken lines in the drawings depict portions of the atmospheric water generator floor unit that form no part of the claimed design.
